CLYDE IRON WORKS, OF DULUTH, MINNESOTA, A CORPORATION OF MAINE.

GATE FOR ORE CHUTES AND THE LIKE.

Application filed September 30, 1924. Serial No. 740,785.

To all whom it may concern:

Be it known that we, JOHN R. MCGIFFERT, and OLA L. BERBY, citizens of the United States, and residents of Duluth, county of St. Louis, State of Minnesota, respectively, have jointly invented a new and useful Improvement in Gates for Ore Chutes and the like, of which the following is a specification, the principle of the invention being herein explained, and the best mode in which we have contemplated applying that principle so as to distinguish it from other inventions.

In connection with ore docks, such as are found at the upper ports of the Great Lakes, the ore intended for transfer to vessels is received in an elevated bin or pocket from which it is discharged through a chute into the hold of a vessel tied alongside the dock. The bins are constructed with sloping bottoms and the discharge openings through which the ore escapes therefrom to the chutes and thence to the vessel hold are normally closed by suitable gates which necessarily have to be of rather heavy construction. The operation of such gates, moreover, entails some special difficulties for they are very apt to become jammed in partially open position due to the rush of the heavy weight of material in the bin. Accordingly, while normally held closed by means of a latch, it is desirable the moment such latch is released that the gate should be raised out of the way of the stream of ore that instantly starts flowing from the bin.

Having the foregoing in mind, a principal object of the present invention is to provide adequate power means for raising and lowering a gate of the type in question and for correlating with such operation of the gate proper the operation of the latching device provided in connection with such gate so as to avoid any danger of the gate becoming jammed on the one hand and so as to insure the closure of the gate on the other hand.

To the accomplishment of the foregoing and related ends, the invention, then, consists of the means hereinafter fully described and particularly pointed out in the claims, the annexed drawings and the following de-

scription setting forth in detail certain mechanism embodying the invention, such disclosed means constituting, however, but one of various mechanical forms in which the principle of the invention may be used. 55

In said annexed drawings:

Fig. 1 is a broken side elevation of an ore dock of the type above referred to, with bin, discharge chute and gate, along with our present improved operating means for such 60 gate; Fig. 2 is a broken front elevation of the same; Fig. 3 is a plan view of the cable winding drum and associated mechanism that constitute the gate operating means proper; Fig. 4 is a side elevation of the 65 mechanism shown in Fig. 3; and Fig. 5 is a front elevation thereof as viewed from the right in Figs. 3 and 4.

It will be understood that the general arrangement of the parts of the ore docks 70 illustrated in Figs. 1 and 2 is typical. Thus, the bin or pocket 1, of which only the extreme lower portion is shown, is disposed below an elevated platform 2. On the latter are carried the tracks for the ore cars by 75 means of which the ore is brought to the dock and transferred to such bins or pockets, these being ordinarily arranged in batteries, that is, a number of pockets is provided side by side lengthwise of the dock so that ore 80 may be discharged therefrom simultaneously through all the hatches of the vessel. Oscillately supported below the bottom line 3 of each bin is a chute or spout 4 shown only in Fig. 1 and there appearing in dotted 85 outline in its raised or inoperative position. When ore is being discharged from the bin, this spout will be dropped so as to extend in a downwardly inclined direction, as need not be further explained.

The gate or door 5, whereby the discharge opening of bin 1 is normally closed, is ordinarily of rectangular outline and is slidably, as well as oscillately, secured at its upper end in two vertical guides 6, one on each side 90 of the path of travel of the gate. Pivotaly attached adjacent the lower end of the gate is one end of a link or bar 7, the outer end of which travels in an inclined guideway 8, and a latch 9, pivotally mounted just above 95 100

such guideway, is disposed so as normally to engage the end of the bar and thereby prevent movement of the latter downwardly along such guideway. In the latched position of the bar, the gate is securely held in the closed position shown in Fig. 1. However, upon swinging the latch out of the path of travel of the bar end, the latter is free to move downwardly along the guideway and thus allow the gate to swing outwardly about its transverse axis of oscillation in guides 6. The moment, however, the gate thus swings outwardly, it must be raised clear of the discharge opening of the bin, otherwise the rush of material through such opening will jam the gate and the weight of the material is so great that it is exceedingly difficult thereafter to release the gate and permit desired free flow of the material. It is of course the weight of the material resting against the gate when closed that makes it impractical to raise the latter directly, i. e., in a straight vertical line.

For the purpose of operating latch 9, a double arm lever 10 is oscillatorily mounted in the supporting framework above and slightly to one side of such latch, one end of said lever being connected by means of a link 10^a with a lever arm 11 projecting from such latch or rather from a common transverse shaft 12 that carries both latch and lever arm. The respective ends of the double arm lever 10 are connected by means of cables or equivalent flexible members 14 with corresponding ends of a double arm lever 15 oscillatorily mounted on platform 2 adjacent the gate operating mechanism 16 and in effect forming a part thereof, as will now be described. A handled lever 17 is centrally fixed to the double arm lever 15 so as to permit the latter to be rocked in either direction as may be desired and obviously such rocking movement will produce a corresponding oscillation of double arm lever 10. Oscillation of the latter in a counter-clockwise direction, as viewed in Fig. 1, it will be noted, serves to raise the latch 9 so as to clear the end of bar 7, while oscillation in the opposite direction lowers the latch back again into operative position.

A cable 20 or equivalent flexible member is employed to raise and lower the gate, such cable being suitably guided over pulleys 21 in the framework of the dock and having its lower end divided into two diverging parts 22 for attachment to lugs or brackets 23, one on each side of the upper edge of the gate. The upper end of cable 20 is attached to a grooved spool or winding drum 24 that forms the main element of the operating mechanism 16, such spool being mounted on a shaft 25 on which is also fixedly secured a gear 26 that meshes with a pinion 27 normally freely rotatable on a drive shaft 28 parallel with said drum shaft 25.

Where a series of bins or pockets 1 is arranged side by side along the dock, the shaft 28 may be carried the entire length and so be disposed to drive the entire series of winding drums 24 or such selected ones thereof as may from time to time be connected therewith. Such connection is controlled by means of a cone clutch 30 of standard construction on shaft 28 adjacent pinion 27, the cone element of such clutch being moved in and out by means of a rocker arm 31 freely oscillatorily about the axis of the double arm lever 15, being preferably thus mounted on the same shaft 15^a that carries said lever. The handled lever 17, whereby such double arm lever 15 is oscillated, as above described, is formed near its lower end with two similar oppositely projecting arms 32, each provided on its inner face with a stop 33 disposed to engage rocker 31 on the corresponding side. It will accordingly be seen that while said handled lever 17 is thus adapted to operate clutch 30, as well as to oscillate double arm lever 15, there will be a predetermined amount of lost motion in the operation of the rocker. In other words, the clutch 30 will be thrown in or out a little after the double arm lever is oscillated to actuate latch 9.

Fixedly attached to shaft 15^a is a horizontally projecting arm 35 with an opening in its free end through which passes cable 20 on its way to drum 24 and secured to said cable is a button 36, so located as to be brought in contact with arm 35 just before gate 5 has been raised to its full open position. Further movement of the button as the cable is wound up thereupon will raise the arm 35 and by swinging the handled lever 17 with stops 33 will serve to throw out clutch 30 through engagement with the appropriate one of said stops with rocker 31.

As shown in Figs. 3, 4 and 5, a flexible brake band 37 is applied to the appropriately enlarged hub 38 of pinion 27, said band being normally placed under tension by means of a weighted arm 39 projecting radially from a shaft 40 to which the free end of said band is attached. A handled lever 41 is in turn attached to said weighted lever 39 so that by pulling on said lever in a clockwise direction, as shown in Fig. 4, the friction of band 37 on hub 38 will be relieved, or in other words, any braking action eliminated. However, when the weighted lever 39 is allowed to drop, the pinion 27 and thus gear 26, with attached drum 24, are held against rotation.

The condition of the parts of the gate operating mechanism, last referred to, in which the brake 37 is applied so as to hold the drum 24 against rotation, is that existing when the gate or door 5 is in its fully raised position. Assuming such gate is thereupon to be closed, following discharge

of the material stored in bin 1, the brake 37 is released to allow the gate to descend under its own weight, thereby unwinding cable 20, the rate of this movement being controlled by the brake. As previously indicated, as the gate drops into closed position, the free end of bar 7 moves outwardly and downwardly along guideway 8, strikes latch 9 and swings radially about latch 9 forcing the bottom of the gate into closed position. The reverse operation, i. e., when the gate is to be opened, requires first that handled lever 17 be swung in clockwise direction, as viewed in Figure 2, so as to raise latch 9. The gate is thereby left free to swing outwardly and immediately following the raising of the latch clutch 30 is thrown in so that the drum 24 instantly begins winding up cable 20, thus raising the gate entirely clear of the discharge opening of the bin. The engagement of button 36 with arm 35 just as soon as the gate has been raised to full open position automatically throws lever 17 to the left as viewed in Figs. 2 and 5, turning latch 9 into position to engage end of bar 7 when the latter again moves downwardly, and stops the winding operation by disengaging clutch 30. The brake band is now again allowed to take hold and the mechanism is ready for a repetition of the cycle of operation just described.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:—

1. In mechanism of the character described, the combination with a vertically slidable gate having also an oscillatory movement about a transverse axis; of means adapted to raise and lower said gate as desired; a latch adapted to engage said gate to prevent oscillation thereof when closed; and means adapted to operate said latch, said means at the same time controlling said gate raising and lowering means, substantially as described.

2. In mechanism of the character described, the combination with a vertically slidable gate having also an oscillatory movement about a transverse axis; of a cable and cable winding means adapted to raise and lower said gate as desired; a latch adapted to engage said gate to prevent oscillation thereof when closed; and means adapted to operate said latch, said means at the same time controlling said cable winding means.

3. In mechanism of the character described, the combination with a vertically slidable gate having also an oscillatory

movement about a transverse axis; of a cable connected with said gate for raising and lowering same; a winding drum for said cable; a clutch controlling operation of said drum; a latch adapted to engage said gate to prevent oscillation thereof when closed; and a lever for operating said latch, said lever being also connected to operate said clutch.

4. In mechanism of the character described, the combination with a vertically slidable gate having also an oscillatory movement about a transverse axis; of a cable connected with said gate for raising and lowering same; a winding drum for said cable; a clutch controlling operation of said drum; a latch adapted to engage said gate to prevent oscillation thereof when closed; and a lever for operating said latch, said lever being also connected to operate said clutch, there being a lost-motion in the connection between the latter and said lever.

5. In mechanism of the character described, the combination with a vertically slidable gate having also an oscillatory movement about a transverse axis; of a cable connected with said gate for raising and lowering same; a winding drum for said cable; a clutch controlling operation of said drum; a latch adapted to engage said gate to prevent oscillation thereof when closed; a double arm lever for operating said latch; a second double arm lever provided with an operating handle; and cables connecting the corresponding arms of said levers, said second lever also having a lost-motion connection with said clutch for operating same.

6. In mechanism of the character described, the combination with a vertically slidable gate having also an oscillatory movement about a transverse axis; of a cable connected with said gate for raising and lowering same; a winding drum for said cable; a driving shaft; clutch controlled gearing adapted to connect said shaft with said drum, whereby the latter may be rotated to wind up said cable and so raise said gate; a brake adapted to control reverse rotation of said drum, whereby said gate is lowered; a latch adapted to engage said gate to prevent oscillation thereof when closed; and a lever for operating said latch, said lever being also connected to operate said clutch.

7. In mechanism of the character described, the combination with a vertically slidable gate having also an oscillatory movement about a transverse axis; of a cable connected with said gate for raising and lowering same; a winding drum for said cable; a driving shaft; clutch controlled gearing adapted to connect said shaft with said drum, whereby the latter may be rotated to wind up said cable and so raise said gate; a brake adapted normally to prevent reverse rotation of said drum, whereby said

gate is lowered; means for releasing said brake when desired; a latch adapted to engage said gate to prevent oscillation thereof when closed; a double arm lever for operating said latch; a second double arm lever provided with an operating handle; and cables connecting the corresponding

arms of said levers, said second lever also having a lost-motion connection with said clutch for operating same.

Signed by us this 26th day of September, 1924.

JOHN R. MCGIFFERT,
OLA L. BERBY.
